COMBINED CONTAINER AND DISPENSER

Karl Brocken, Aurora, Ill., assignor to Anfinsen Plastic Molding Inc., Aurora, Ill., a corporation of Illinois

Filed Feb. 26, 1963, Ser. No. 73,722

Term of patent 3½ years

(Cl. D58—17)

FIG. 1 is a perspective view of a combined container and dispenser, in open position, showing my new design;

FIG. 2 is a perspective view thereof in closed position; and,

FIG. 3 is a top plan view thereof in open position.

The bottom of the combined container and dispenser is plain.

The characteristic features of my design reside in the combination of a container and dispensing cover wherein the cover is attached to the outer peripheral edge of the container by a hinged strap and the pouring opening closure is attached to the outer peripheral edge of the cover by hinged strap, all in a straight line as shown.

I claim:

The ornamental design for a combined container and dispenser, substantially as shown and described.
